FUEL SAVING DEVICE

Filed Sept. 25, 1929

Inventor
WILLIAM KREFT

BY: *Ben V. Gillman*
Attorney

UNITED STATES PATENT OFFICE

WILLIAM KREFT, OF ST. LOUIS, MISSOURI

FUEL-SAVING DEVICE

Application filed September 25, 1929. Serial No. 395,101.

My invention relates to improvements in fuel-saving devices, and has among its objects the production of such a device that may be placed in the smoke stack leading from a heating plant such as a furnace, boiler or the like, and which may be used to utilize the stack gases that would otherwise be wasted.

The invention has among its objects, the production of such a device which shall be simple, convenient to install and operate, economical, sturdy, and reliable and efficient for use wherever found applicable.

Another object of my invention is to provide a fuel saver of the kind described, which will also act as a smoke abater, and which may be easily cleaned at suitable intervals.

Many other objects and advantages of the construction herein shown and described, will be obvious to those skilled in the art to which this invention appertains, from the disclosures herein given.

To this end, my invention consists in the novel construction, arrangement, and combination of parts herein shown and described, and more particularly pointed out in the claims.

In the drawings, wherein like reference characters indicate like or corresponding parts throughout,

Figure 1 is a vertical section through my improved device, partly in elevation, as arranged in position; and

Figure 2 is a plan view of an element thereof.

In the drawings, wherein I have illustrated a preferred embodiment of my invention, A indicates any type or design of heating plant such as a furnace for coal, oil, etc., in which heat is generated, and from which the otherwise wasted gases pass into the air through the smoke stack indicated at B and B'.

In order to utilize these ordinarily wasted heated gases that pass out through the stack, I interpose a device between the adjacent sections of the stack B—B', preferably near the

outlet from the furnace, as the gases are hottest at this point, said device serving not only to heat a liquid such as water therein, but serving the additional purpose of reducing the amount of smoke and the density of the same 50 exuded from the top of the stack.

The device preferably comprises a tubular element 1, of considerably larger diameter than the smoke stack so as not to cut down the required draft, the ends of the element having 55 the end plates 2 and 3 therefor, somewhat as shown in Figure 2, each of the end plates having openings 4 therethrough to permit of the free passage of gases through the stack.

A specially constructed dome section 5 60 may be placed at the upper end of the tubular element or container 1, to cover the same thereat, above the end member 2, said dome section communicating with the section B' of the stack.

A spirally coiled conduit such as the pipe 6 having the inlet end 7 and outlet end 8, is arranged within the tubular element 1, adjacent the inside periphery thereof, and through which water or other liquid may be conducted 70 for any purpose, such as for providing hot water or the like. If desired, a metallic packing material, such as crinkled copper strands 9, or other good heat-conducting material, may be interposed between the adjacent coils 75 of the pipe 6 so as to prevent free passage therebetween.

A spirally-extending plane 10 is arranged within the container, the axis of the spiral being preferably coincident with the axis of the coil 6, and the periphery of the member 10 being adjacent the coil, so as to define a spiral passageway and whereby the gases passing upwardly through the stack will be directed in a winding, tortuous, spiral path, being deflected outwardly toward and onto the coiled pipe 6 to heat the liquid therein. If desired, the surfaces of the member 10 may be covered with asbestos or other suitable material, 80 85 90

to cause eddying currents therein and otherwise slow up the speed of the gases, and to retain the container in as highly a heated condition as possible. To this end, the outer surface of the container may be covered with suitable insulating material such as asbestos.

The area of the passageway through the spiral means is preferably designed so as to be substantially equal to the stack sections B 10 and B', so that although the speed of the gases is slowed up in passing through the container, yet the draft is not reduced, or at least not materially reduced.

In order to permit the heat to reach the pipe 6 and yet prevent most of the solid particles in the smoke from reaching and settling on the pipe to thereby impair its efficiency, I have preferably arranged a screen 11 to surround the member 10, between the latter and the pipe 6, the screen being closely adjacent the peripheral edges of the member 10 for a purpose to be hereinafter described.

With the construction just described, all of the heated gases and solid particles discharged upwardly of the stack will travel a spirally circuitous path through the container interposed between the stack sections B and B', wherein their speed is reduced and the heat is utilized to heat the liquid that is in 20 the pipe 6, and the solid particles will strike against the vane member and the screen and either fall back into the furnace or cling to or be deposited on these parts.

In order to provide means for easily and readily cleaning the parts that are most apt to receive deposits of these solid particles thereon, I have provided means for scraping the screen. To this end the vane member is carried or fixed to a shaft 12 whose lower end 40 rests upon a ball bearing 13 placed centrally within the end plate 4, said ball being supported upon a wear block 14 resiliently and adjustably held in place by a spring 15 whose spring pressure is adjustably regulated by a 45 screw 16.

Driving means, such as the meshing gears 17 and 18 are arranged at the other end of the shaft, the gear 17 being keyed or otherwise connected to the shaft, and there being 50 an annular ball bearing 19 at said end. The gears are driven through a shaft 20, either by hand or through other source of power, as for example a motor, (not shown).

Rotation of the deflector element 10 will 55 cause its edges to scrape off the sediment that may have become deposited upon the screen, and also shaking off those particles that may have settled upon itself, these particles falling through the openings 4 of the bottom 60 plate element 3, either into the furnace or onto the bottom portion of the inside of the stack section B. A door 21 may be placed on said section of the stack, to form a closure for a suitable opening 22 therein, and by 65 means of which cleaning out of the deposits

may be effected, and whereby the screw 16 may be adjusted.

Having thus described my invention, it is obvious that various immaterial modifications may be made in the same without departing from the spirit of my invention; hence I do not wish to be understood as limiting myself to the exact form, construction, arrangement and combination of parts herein shown and described, except as limited by the claims.

What I claim as new and desire to secure by Letters Patent is:

1. In a device of the kind described and in combination with a smoke stack, a container adapted to be arranged in the path of the gases through said stack, a coiled pipe in said container, a screen covering said pipe, and a rotatable spirally extending vane in said container to define a spirally-extending passageway therethrough to deflect said gases onto said pipe, the rotative movement of said vane acting to remove solid matter from said screen.

2. In a device of the kind described and in combination, a container forming a portion of a smoke stack, a spirally coiled pipe within said container and adapted to have liquid conducted therethrough, metal packing means between adjacent coils of said pipe to prevent free passage therebetween, means forming a spiral passageway through said container and opening adjacent said coiled pipe so as to deflect the heated gases thereonto, a circularly extending screen between the periphery of said last-mentioned means and said pipe, and means for rotating said spiral-passageway forming means to remove solid matter from the screen.

3. In a device of the kind described and in combination with the smoke stack of a heating plant, a container adapted to be arranged in the path of the heated gases from said heating plant and forming a section of said stack, a spirally extending deflector within said container, a perforated wall closely encircling said deflector and spaced from the inside wall of the container, and means in the space between said wall and container for conducting the heat therefrom whereby said heated gases will be deflected radially outwardly into said space to be utilizable therein, said wall acting as a filter for solid particles deflected by said deflector means.

4. In a device of the kind described and in combination with a smoke stack, a container adapted to be arranged in the path of the gases through said stack, a length of pipe in said container, a perforate inner wall spaced from said container wall, said pipe being between both of said walls, and a rotatable spirally extending vane in said container and engaging said inner wall to define a spiral passageway through said container to deflect said gases toward said pipe, the rotative

movement of said vane acting to remove solid matter from said inner wall.

5. In a device of the kind described and in combination with a smoke stack, a container adapted to be arranged in the path of the gases through said stack, a coiled pipe in said container, a vane movably mounted in said container to define a spiral passageway therethrough to deflect said gases toward said 10 pipe, and a perforate wall between said pipe and vane, the movement of said vane acting to remove solid matter from said wall.
